UNITED STATES PATENT OFFICE

2,062,791

SLIDER FOR FASTENERS

Robert C. Legat, New Britain, Conn., assignor to
 G. E. Prentice Manufacturing Company, New
 Britain, Conn., a corporation of Connecticut

Application April 8, 1936, Serial No. 73,212

10 Claims. (Cl. 24—205)

This invention pertains to slide actuated fasteners and more especially to an improved slider for such fasteners and to gravity-actuated locking means for preventing or resisting unintentional movement of the slider longitudinally of the fastener.

The patents to Prentice No. 1,778,338 and Legat No. 1,919,662 disclose sliders provided with locking means, and in each of these patents the slider is shown as having an aperture or window in its front wing with a locking element fitting loosely within such aperture or window, and means forming a part of the pull tab operative at times to press the locking element into locking engagement with the fastener units. In the patented devices the pull tab is furnished with a transverse enlargement or cam adjacent to its point of pivotal support and in order to insure a secure locking effect it is recommended to apply pressure to the pull tab so as positively to swing the lower end of the tab rearwardly and past the vertical plane.

While the devices of the aforementioned patents are highly desirable and effective for the purpose, the present invention represents an improvement over such prior devices in that it provides for effective locking in a wholly automatic manner in response to the action of gravity upon the pull tab when the latter is released by the operator and in the permissive employment of a pull tab of simplified form. Furthermore the present invention provides a locking slider which operates very smoothly, exhibits no tendency to stick, bind or catch when operated, and which does not injure or harmfully displace the fastener units.

In the preferred construction herein illustrated, the locking means is of double acting type, that is to say, it is effective for locking, whether the slider be applied in such a way as to close the fastener by upward or downward movement respectively, although in its broader aspects it is not essential that the locking means be of double acting type.

In the accompanying drawings, wherein a desirable embodiment of the invention is illustrated by way of example,—

Fig. 1 is a fragmentary front elevation of a slide actuated fastener having opposed series of interlocking fastener units mounted upon flexible supports or stringers and provided with a slider, arranged to close the fastener by upward movement of the slider, embodying the present invention;

Fig. 2 is a view similar to Fig. 1, but with the

parts arranged for closing the fastener by downward movement of the slider;

Fig. 3 is a front elevation of the improved slider removed from the fastener;

Fig. 4 is a rear elevation of the slider of Fig. 3; 5

Fig. 5 is an edge elevation, partly in vertical section and to larger scale, of the slider of Fig. 3;

Fig. 6 is a plan view of a blank useful in forming the improved slider;

Fig. 7 is a large scale side elevation of the improved locking element; 10

Fig. 8 is a plan view, to smaller scale, of the locking element;

Fig. 9 is a rear elevation of the locking element to the same scale as Fig. 8; 15

Fig. 10 is a vertical section, with parts broken away, showing the improved slider as arranged to close the fastener by upward slider movement and showing the locking element in non-locking position with the pull tab positioned for moving 20 the slider longitudinally;

Fig. 11 is a view similar to Fig. 9 showing the pull tab depending in substantially parallel relation to the front wing of the slider and showing the locking element in operative engagement with 25 one of the fastener units;

Fig. 12 is a view similar to Fig. 11, but with the slider arranged for closing the fastener by downward slider movement;

Fig. 13 is a front elevation of the pull tab, removed from the slider; and 30

Fig. 14 is a section on the line 14—14 of Fig. 13.

Referring to the drawings, the numerals 1 and 2 indicate respectively two flexible supports or stringers carrying series of fastener elements 3 and 4, respectively, such elements being of any usual type but preferably of the kind disclosed in the patent to Prentice No. 2,029,585, dated February 4, 1936. The stringers 1 and 2 are furnished with top end-stops 5 and 6, respectively, 40 and at the lower end of the fastener is a bottom stop 7 which may or may not be of the separable type, according to the use to which the fastener is to be put. The actuating slider 8 comprises the front wing 9 and the rear wing 10 united at their 45 upper ends by a connecting portion 11 (Fig. 5) the wings being spaced apart to provide proper channels for the passage of the edges of the stringers with the fastener units mounted thereon. One or both of the wings of the slider is 50 furnished with lateral flanges such as the flanges 13 and 14 (Fig. 5) for engagement with the outer or remote ends of the fastener units and to define the outer margins of the channels in which the 55 series of fastener units are received. These

- channels are separated at the upper part of the slider by means of a divider or separator 15, here shown as a rivet having an enlargement 16 which bears against the front surface of the front wing 5 and which is headed over at 17 against the rear surface of the rear wing, thereby not only performing the function of a divider but also imparting substantial stiffness and rigidity to the slider.
- 10 Preferably the front and rear wings and the neck portion are formed as an integral piece from sheet material,—a blank of appropriate shape for the purpose being illustrated in Fig. 6. This blank comprises the front wing portion 9^a and the rear wing portion 10^a integrally joined by the neck portion 11^a. The part 9^a is furnished with an opening 15^a and the part 10^a with an opening 15^b designed for the passage of the rivet 15. The front wing member 9^a is also furnished with a pair of openings 16 and 17, elongate longitudinally of the wing and spaced symmetrically at opposite sides of its longitudinal axis and separated by a portion of the metal of the front wing which forms a bridge member 9^x. These openings or windows 16 and 17 are designed to receive, respectively, spaced parts of the locking element 18 illustrated more particularly in Figs. 7 to 9 inclusive. This locking element 18 is conveniently formed from sheet material and is substantially U-shaped in transverse section, having the substantially parallel leg portions 19 and 20 integrally joined by the transverse portion 21. Each of the leg portions is terminated by substantially parallel top and bottom end surfaces 22 and 23, respectively, and is of a length and thickness such that it may be received in one of the respective openings 16 or 17 of the front wing, and to fit loosely within such opening. The leg 19 is terminated by the inclined convergent cam surfaces 24 and 25 which meet at the point 26 which forms the apex of a triangular locking cusp or tooth, it being noted that the slope of the cam surface 25 is steeper than that of the cam surface 24.
- 45 The free end or edge of the leg member 20 is likewise furnished with convergent cam surfaces 24^a and 25^a, respectively, meeting at the point 26^a to form a locking cusp or tooth similar to that of the leg 19, it being noted, however, that the more steeply inclined cam surface 25^a of leg 50 20 is opposite to the less steeply inclined cam surface 24 of the leg 19. The apices 26 and 26^a of the two locking cusps are spaced apart longitudinally of the locking element a distance substantially equal to the thickness (longitudinally of 55 the slider) of one of the fastener units.
- 55 The rivet 15 preferably is provided with a stiff and preferably substantially rigid tab-supporting portion 21 which overlies the front face of the front wing 9 and which, as here illustrated, terminates at the point 28 somewhat above the lower end of the front wing. If desired, this tab-supporting portion 21 may extend down substantially to the lower end of the wing and may be anchored at its lower end by means similar to that shown in the patent to Legat No. 1,919,662, wherein a somewhat similar tab-supporting element is illustrated. The supporting element 21 is furnished with a recess 29 in its inner edge, such recess being open toward the front surface of the front wing and being adapted to receive the pivot member 30 of the pull tab 31. This pull tab 31 (Figs. 13 and 14) is conveniently formed from sheet material of substantially uniform thickness and is provided with an elongate opening 32 for the reception of the hook-like end portion of the sup-

port 21. As may be noted from inspection of Fig. 12, this pivot portion 30 is of less thickness, longitudinally of the tab, than in a direction at right angles thereto, that is to say, the top-to-bottom thickness of the pivot (Fig. 14) is less than 5 the thickness of the sheet material from which the tab is made. This pull tab is preferably assembled with the support 21 by slipping the end 10 28 of the support through the opening 32 and moving the tab until the pivot member 30 is disposed in the recess 29 in which position the pivot member 30 overlies the transverse portion 21 of the locking element 18, which has been positioned to straddle the bridge member 9^x with its legs 15 19 and 20 disposed in the windows 16 and 17, respectively. The rivet 15 is now set and headed over at 17, thus permanently retaining the tab and the locking element in assembled relation to the slider body. While this mode of assembly is preferred, it is possible first to set the rivet and 20 head it over at its rear end and then by bending the tab-supporting portion 21 to assemble the locking element and tab in proper position.

Having assembled the parts in one or another of the ways mentioned, and having assembled 25 the slider with the stringers, the slider may be moved longitudinally of the fastener for opening or closing the fastener by swinging the tab out substantially to the position illustrated in Fig. 10. In this position the pivot member 30 30 is disposed with its longer dimension vertically and the locking element 18 is free to move forwardly to a slight extent, but sufficient so that its triangular cusps substantially clear the forward edges of the fastener units. Such forward 35 movement of the fastener element for clearing the units is facilitated by the long cam slopes 24 and 24^a, respectively, (according to the direction in which the slider is moved) such long slopes riding along the surfaces of the units with a 40 smooth action and causing the locking element to move forward as is permitted by the pivot member 30 when the tab is disposed in the actuating position.

However, when the slider has been moved to 45 the desired position of adjustment and the tab is released, the tab tends, under the action of gravity, to swing down into a position wherein it is substantially parallel to the front face of the front wing, as illustrated in Figs. 11 and 12, 50 accordingly as the fastener is arranged as shown in Figs. 1 or 2, respectively. In so moving, the thicker dimension of the pivot member 30 is caused to lie horizontally. The dimensions of the pivot 30 and the recess 29 are so chosen that 55 when the tab occupies this position, the locking member 18 is held inwardly with its triangular locking cusps disposed between adjacent units of the series. When thus entered between adjacent units, if force be applied to move the slider downwardly (Fig. 11) the steeper cam surface 25 engages one of the units, for example the unit 3^a, and effectively prevents movement of the slider in this direction. Since the surface 25 is inclined to the direction of slider movement, it operates as a cam to move the slider slightly, under the impeding force exerted by the downwardly swinging tab so that the entry of the cusp between adjacent units is facilitated and made certain, whereas if the surface 25 60 were perpendicular to the direction of slider movement, some difficulty might be experienced in causing the cusp or tooth to be brought into proper registry with the space between adjacent units. By making the surfaces 24 and 24^a with 65 70 75

a relatively long and gentle slope, the locking element may be moved freely along the fastener when the pull tab is in the horizontal position of Fig. 9.

5 This locking device as illustrated is designed to lock the slider whether the slider be mounted on the fastener to close the fastener by upward or downward movement, for since the locking element 18 is symmetrically constructed, one of 10 its legs 19 or 20, respectively, is adapted to function as a locking device whenever the pull tab lies parallel to the front wing of the slider, as shown in Figs. 11 and 12, by way of comparison.

While it is preferred to employ a locking device 15 of symmetrical type, adapted for locking in either direction, it is contemplated that the locking device may be made so as to lock in one direction only, for example by placing the steep cam slopes 25 and 25^a at the same end 20 of the locking element rather than at opposite ends, or by providing but one locking cusp.

The slider thus constructed is very free to move up and down, and thus to perform its intended function when the pull tab is disposed horizontally, but effectively prevents unintentional movement of the slider whenever the tab is released, and it is not necessary to push the pull tab rearwardly of the vertical plane in order to obtain the desired locking action, since the tab drops down into the vertical position under the action of gravity without any special manipulation by the operator. It is further to be noted that no springs are required and that the locking effect, as well as the proper manipulation 35 of the slider, is obtained by the use of but two moving parts, to wit, the locking member 18 and the very simple pull tab 31.

While I have herein illustrated one desirable embodiment of the invention by way of example, 40 it is to be understood that the invention is not necessarily limited to the specific details herein illustrated nor to any particular materials nor to exact dimensions, except such relative dimensions as may be necessary to obtain the locking effect.

45 I claim:

1. A slider for slide actuated fasteners, said slider comprising spaced substantially parallel front and rear wings united by a neck portion, 50 a pull tab support carried by the slider, said support including a part which extends longitudinally of the front wing closely adjacent to the outer surface of the latter and which has a bearing recess open toward the front face of said wing, a pull tab of substantially uniform thickness, said pull tab having a pivot portion disposed in the bearing recess of the support, the pivot portion being of substantially the full transverse thickness of the material of the tab 55 but being of a lesser thickness longitudinally of the tab, the slider comprising a movable locking element which is held in locking position by said pivot portion of the tab when the tab swings downwardly into a position such that it is disposed substantially parallel to the front wing of the slider in response to the action of gravity.

2. A slider for slide actuated fasteners, said slider comprising front and rear wings, the front wing having provision for the reception of a relatively movable locking element, a locking element 70 associated with the front wing, a pull tab support carried by the slider, said support including a part extending longitudinally of the front wing and having a bearing recess open toward the front 75 face of the front wing, and a pull tab of sheet

material, said pull tab having an integral pivot portion disposed in the recess in said support, said pivot portion being of substantially the normal transverse thickness of the material but being of less thickness longitudinally of the tab, 5 the pivot portion of the tab being so disposed relatively to the locking element as to hold the latter in operative position when the tab is permitted to drop, under the action of gravity, into a position such that it is disposed substantially parallel to the front wing of the slider.

3. A slider for slide actuated fasteners, said slider comprising front and rear wings, the front wing having a pair of spaced apertures arranged at opposite sides, respectively, of the longitudinal axis of the wing, a locking element comprising spaced parts which extend inwardly through the respective openings and a transverse portion disposed at the outer side of the front wing, a pull tab support carried by the slider, said support 20 including a part disposed forwardly of the front wing and substantially midway between said apertures, said part having a recess open toward the front surface of the front wing, and a pull tab comprising a pivot portion disposed in said recess forwardly of the transverse portion of the locking element, said pivot portion being of such transverse thickness that, when the tab is allowed to drop until it is substantially parallel to the front wing, it bears both against the transverse portion 30 of the locking element and against the forward wall of the recess thereby to hold the locking element in locking position, said pivot portion being of lesser thickness longitudinally of the tab so that when the tab is disposed substantially perpendicular to the front wing the locking element is free to move forwardly from locking position.

4. A slider for slide actuated fasteners, said slider comprising front and rear wings, the front wing having an aperture therethrough, a locking 40 element comprising a portion which extends inwardly through said aperture and a part which overlies the front face of the front wing, a pull tab support carried by the slider, said support including a part disposed forwardly of the front wing and which bridges said transverse part of the locking element and which has a recess open toward the front wing, and a pull tab of sheet material comprising a pivot disposed in said recess, said pivot being of a transverse thickness 50 substantially equaling that of the material of the tab but being of less thickness longitudinally of the tab, said pivot being arranged to contact the transverse portion of the locking element, the parts being so dimensioned and arranged that 55 when the pull tab is allowed to fall so that it hangs substantially parallel to the front wing, the pivot holds the locking element in operative position and when the tab is perpendicular to the front face of the front wing the locking element is free to move out of locking position.

5. A slider for slide actuated fasteners, said slider comprising spaced front and rear wings, one of said wings having a pair of apertures therethrough separated by a bridge piece, a locking 65 element of substantially U-shape in section comprising a transverse portion and substantially parallel legs, said locking element straddling said bridge piece with the free ends of the legs of the locking element directed inwardly toward the interior of the slider, a pull tab and tab-supporting means carried by the slider, the pull tab comprising a movement-limiting part which is always disposed inwardly of the transverse portion of the locking element and which is engageable with the 70 75

latter to hold the locking element in locking position.

6. A slider for slide actuated fasteners, said slider comprising spaced front and rear wings, one of said wings having a pair of apertures therethrough separated by a bridge piece, a locking element substantially U-shape in transverse section comprising a transverse portion and substantially parallel spaced legs, each leg being 10 elongate longitudinally of the slider, each leg of the locking element having a locking cusp at its free end, said locking element straddling the bridge piece of the front wing with its legs projecting rearwardly through the respective apertures, a pull tab support, and a pull tab carried by the support, said tab being provided with a part which is always disposed forwardly of the transverse portion of the locking element and which is operative by engagement with said transverse portion to limit forward movement of the locking element.

7. A slider for slide actuated fasteners, said slider comprising spaced front and rear wings, one of said wings having a pair of apertures therethrough separated by a bridge piece, a locking element of substantially U-shape in transverse section, said locking element consisting of sheet metal and comprising spaced parallel legs united by a transverse portion, the free end of each leg being shaped to form a triangular locking cusp, said locking element straddling the bridge piece with its legs extending rearwardly through the apertures in the wing, and a pull tab and tab-supporting means carried 30 by the slider, the pull tab comprising a part engageable with the transverse portion of the locking element to hold the latter in locking position.

8. A slider for slide actuated fasteners, said slider comprising spaced front and rear wings, one of said wings having a pair of apertures therethrough separated by a bridge piece, a locking element of substantially U-shape in trans-

verse section, said element comprising spaced, substantially parallel legs, the free end of each leg comprising inclined convergent cam surfaces, one of the cam surfaces at the end of each leg having a steeper slope than the other cam surface, said locking element straddling the bridge piece with its legs projecting rearwardly through the openings in the front wing, a pull tab, tab-supporting means carried by the slider, and a part carried by the pull tab and engageable with said transverse portion of the locking element to hold the latter in locking position.

9. A slider for slide actuated fasteners, said slider comprising spaced front and rear wings, one of said wings having a pair of apertures therethrough separated by a bridge piece, a locking element of substantially U-shape in transverse section, said element comprising spaced parallel legs, the free end of each leg comprising convergent cam surfaces meeting at an angle to form a locking cusp, the slope of one cam surface being steeper than that of the other, the cam surface of steeper slope of one leg being opposite to the cam surface of lesser slope of the other leg, and means for pressing said locking element rearwardly, thereby to engage its locking cusps with the fastener elements.

10. A slider for slide actuated fasteners, said slider comprising spaced front and rear wings, one of said wings having a pair of apertures therethrough separated by a bridge piece, a locking element of substantially U-shape in transverse section, said element comprising spaced, substantially parallel legs, the free end of each of said legs comprising inclined convergent cam surfaces meeting at an angle to form a locking cusp, the apices of the locking cusps of the two legs being disposed respectively in transverse planes which are substantially one fastener unit apart, and means carried by the slider for actuating the locking element.

ROBERT C. LEGAT.
